Primary Examiner — Deanna L Pratt(74) *Attorney, Agent, or Firm* — Cantor Colburn LLP(57) **CLAIM**

We claim, the ornamental design for a display screen portion with icon, as shown and described.

DESCRIPTION

FIG. 1 is a front view of a display screen portion with icon showing our new design; and,

FIG. 2 is a front view of a display screen portion with icon showing a second embodiment of our new design.

The broken line showing of the display screen portion illustrates the environment of the claimed design and forms no part thereof.
